CLAIM

The ornamental design for a Universal Gutter Guard Cleaning Brush, as shown and described.

DESCRIPTION

FIG. 1 is a top, rear perspective view of an embodiment of a universal gutter guard cleaning brush showing my new design;

FIG. 2 is a bottom perspective view thereof;

FIG. 3 is a bottom perspective view, shown in an environment, thereof;

FIG. 4 is a top plane view thereof;

FIG. 5 is a rear plane view thereof;

FIG. 6 is a front plane view thereof;

FIG. 7 is a left plane view thereof; and

FIG. 8 is a right plane view thereof.

In FIG. 3, the broken lines are for the purpose of illustrating environment only and forms no part of the claimed design

1 Claim, 6 Drawing Sheets
